GLASS FIBER DRAWING MECHANISM WITH
MEANS FOR ACCENTUATING STRAND DIS-
CHARGE

Joseph F. Courtney, Evanston, and Adelbert C. Radtke, Chicago, Ill., assignors to International Harvester Company, a corporation of New Jersey.

Application May 11, 1951, Serial No. 225,883

7 Claims. (Cl. 49—17)

1

This invention relates to a novel apparatus for attenuating a thermoplastic material and has specific reference to the manufacture of glass fibers in the making of glass strands and the like.

Elemental glass fibers are characterized by low tensile strength, susceptibility to abrasion and fracture and extreme fragility and brittleness. Due to this nature of the material and the high speed for drawing the material into fiber form, extreme difficulty has been experienced in providing a satisfactory drawing mechanism which will afford a positive grasp on the strand without deformation and provide a sustained substantially even pull on the strand to obtain approximately uniform characteristics with regard to flexibility, diameter, texture, etc. throughout its length.

A general object of the invention is to devise a novel drawing mechanism which obtains a gentle grasp on a substantial length of a strand and effects an approximately uniform pull on the strand without imposing high transverse stresses thereon.

A further object is to obtain an arrangement which provides a grasp on the strand by continuously moving opposed endless surfaces moving about predetermined axes in such manner as to utilize the centrifugal forces thereon to bias the surfaces towards each other and produce a grasping effect on the strand.

A more specific object is to provide a drawing device presenting opposed continuous surfaces receiving an extensive length of the strand therebetween, at least one of these surfaces being directly actuated and at least one of these surfaces being yieldably urged against the strand by impressing a centrifugal and/or other force thereagainst.

In several arrangements, a plurality of opposed belts are employed and arranged to utilize the centrifugal force to grasp the strand and in several of these embodiments the grasping action is accentuated by causing the strand and belts to move at their grasping areas along a curved or sinuous path.

A more specific further object is to provide such a strand attenuating device with novel means for accentuating discharge of the strand from the device.

These and other objects of the invention will become more apparent from the specification and drawings wherein:

Figure 1 is a side elevational view of one embodiment of the invention.

Figure 2 is a side elevational view of a still further embodiment of the invention.

2

Figures 3 to 5 illustrate another modification. Figure 3 is comparable to Figures 1 and 2; Figure 4 is a radial sectional view on the line 5—5 of Figure 3; and Figure 5 is a fragmentary edge view thereof.

Figures 6 and 7 illustrate a still further embodiment of the invention, Figure 6 being a side elevational view thereof, and Figure 7 a top plan view.

Referring now to the embodiment shown in Figure 1, the furnace 2 is provided with a die plate 4 through which a plurality of filaments 18 flow by gravity, said filaments being gathered initially by the workman and drawn in a fan arrangement downwardly over an applicator assembly 12 and then pulled below the applicator assembly against a side of sheave 14 through a V-groove 16 therein, the filaments discharging from the gathering sheave in compacted form and forming the strand 18. The strand 18 is then pulled downwardly and in a direction towards the sheave and then passed through the rotating drawing mechanism generally indicated 100, said mechanism including an endless drive belt 102 and an idler belt 104, disposed in a substantially vertical plane.

The drive belt 102 is looped under a pulley 106 which is driven through a shaft 108 by a motor 110. The upper extremity of the belt is trained over a pulley 112. Similarly, the idler belt 104 is looped over a pulley 114 and under a pulley 116. The axes of rotation of all of these pulleys are substantially parallel and preferably horizontal. The belts 102 and 104 are arranged in the form of ovals and disposed with the advance flights 118 and 120 respectively alongside each other and with the outer surfaces thereof in facing relationship for receiving the strand therebetween, said strand being guided to the drawing means by a centering fork 122 or grooved idler guide sheave. The axes of rotation of the pulleys 106 and 116 are preferably fixed and the axes of rotation 112 and 120 of the pulleys 112 and 114 are adjustable. As shown in Figure 2, a pulley or roller 128 bears against the backside of flight 118 and is journaled as at 132 on a substantially horizontal axis to the lower end of an arm 134 which is pivoted on a preferably fixed horizontal axis 136 intermediate the ends thereof. The arm 134 rotatably supports at its upper end on a substantially horizontal axis as at 138 a roller 130 which is engaged with the backside of the advance flight 120 of the belt 104. The rollers 128 and 130 are biased contra-directionally with respect to the vertical plane passing therebetween in order

to deflect the advance flights from normally vertical lines to a sinuous or curved path whereby the strand between the advance flights and the grasping lengths of the belts are caused to move or sinuate along a gentle sinuous or curved route. This arrangement permits the application of light transverse clasping or grasping pressure against the strand along an extended length thereof and at the same time affords an efficient frictional engagement between the strand and the belts which is amplified by the wedging tendency between the belts and strand such that sufficient force is applied along a continuous length to provide for effective drawing of the strand. It will be noted that the belts rotate in the direction of the arrows.

The arm or lever 134 is biased in a direction urging the rollers 128 and 130 against the respective flights by means of a tension spring 149 which at one end is hooked as at 142 to the arm 134 intermediate points 132 and 136 and at the other end is fixed as at 144 to the right of lever 134. The pulleys and rollers are disposed far enough apart to admit a workman's hand between flights 118 and 120 without injury.

It will be understood that all of the strand which discharges from the drawing means 110 prior to the attainment of desired drawing rate is preferably discarded and that when a strand is of correct dimension, it is passed through the blower 46 as in our companion application for Glass Fiber Drawing Mechanism and Process, Serial No. 221,596, filed April 18, 1951, said blower being supported immediately below the discharge of the drawing means and depositing the strand 18 into the canister 48. The blower 46 pulls at the strand 18 in excess of the discharge rate of the drawing means but with slipping effect so as not to break the strand. In addition, the rotation of the belts develops centrifugal forces which tend to throw the advance flights of these belts towards each other whereby producing a gentle grasping effect along an extensive length of a strand. Static electricity dischargers 139 may be provided.

Referring now to Figure 2 the drawing means generally designated 200 comprises an entry zone 202 between the upper ends of advance flights or sections 204 and 206 of belts 208 and 210 which on their outer or opposed sides are arranged in contact with a vertical length of strand 18 which adjacent to the entry zone is guided by a centering fork 212, the lower end of the strand discharging below the belts through the nozzle 46 which is applied to the strand after it attains a predetermined size as in all of the previous embodiments. The belt 208 is looped over a pulley 214 and passes under a pulley 216. Similarly, the belt 210 is trained over a pulley 218 and looped under a pulley 220. The belts and pulleys are disposed in a common generally vertical plane. The pulleys are rotatable on substantially parallel preferably horizontal axes and the pulleys 218 and 220 are preferably vertically offset with respect to the pulleys 214 and 216 and arranged in partially vertical overlap therewith so as to produce a curved or sinuous path to which the strand is caused to conform as it travels along the belts. This arrangement effects a gentle gripping action on the strand which is augmented by centrifugal force tending to throw the belts toward each other at their leading lengths. To make this action more aggressive especially at the entry zone both belts are driven

through pulleys 222 and 224 and connected to pulleys 214 and 218 respectively. The pulleys 222 and 224 are driven by a belt 226 which is trained on a pulley 228 driven by a motor 230, 5 said belt 228 having its upper flight passing over the top of an idler pulley 232 and then continuing around the far side of pulley 222 and continuing into the lower flight 234 of the belt which passes over the pulley 224 and then joins 10 around the far side of pulley 228 with the other end of top flight 236 of the belt.

Referring now to Figures 3 through 5, the strand 300 may be guided within a transaxially diagonal groove 302 in the periphery of a guide wheel 304 rotatably mounted as at 306.

The strand is directed downwardly to an entry zone 308 of a drawing mechanism generally designated 310.

The mechanism 310 comprises four intercalated pulleys or wheels 312, 314, 316 and 318. A flat belt 320 is trained around the peripheries of pulleys 312 and 316 and another flat belt 322 is trained about pulleys 314 and 318. Due to the arrangement of the pulleys, the advance 20 flights 324 and 326 of belts 320 and 322 are caused to substantially assume the form of a sinusoidal curve to afford a grasping zone for engaging the strand 300 entered at one or upstream end of the mechanism between the belts 30 at the entry zone at the pulleys 316 and 318, and discharging at the other downstream end at the discharge zone 328 from between the segments of the belts on pulleys 312 and 314. It will be observed that the strand 300 which may be a 35 composite of several strands is thus sinuated through the drawing means and grasped along an extensive length thereof. The present design, as heretofore stated, utilizes preferably flat belts. In order to retain these belts on the pulleys 40 316 and 318, the outer peripheries of these pulleys are crowned convexly outwardly, however, the crest of the crown is formed cylindrical about the axis to provide a width coextensive with the lateral extent of groove 302 in the guide sheave, 45 the groove shifting the strand laterally across the belts to prevent the development of a single track depression in the belts. It will be understood that the axes of rotation of pulleys 312 and 318 are preferably mounted on tensioned adjustable 50 axes and the pulleys 314 and 316 on fixed axes.

The specific feature of this design is to pass the strand through a surface area of substantially maximum curvature and is especially desirable for drawing several strands simultaneously which requires maximum grasping and pulling effort.

Each pulley is preferably designed to have a peripheral extent of about one foot in length and to be rotated at the peripheral speed of approximately 10,000 feet per minute. Thus intense centrifugal force is developed to bias the advance flights of the belts toward each other to accentuate the grasp on the strand. In addition, the tremendous speed of the pulleys tends to discharge the strand tangentially to the peripheries of the segments of the belts trained about pulleys 312 and 314.

The stripping means in the present embodiment comprises a series of alternating flat areas 70 or facets 330 and cylindrical segment areas 332 on the outer peripheries of pulleys 312 and 314. The arrangement of these areas develops transverse oscillation of the belts at the discharge zone which serve to cast off the strand from the belts. Furthermore, the sharp change of direc-

tion of the belts from the projected path of the strand also disengages the strand therefrom so that the strand may discharge directly into container 334.

The drawing mechanism may be suitably powered from a motor 336 through a belt and sheave linkage 338 driving sheave 314.

Referring now to the modification in Figures 6 and 7, it will be seen that the general concept is the same as in the previous embodiments but provides a more compact arrangement and an intermediate grasping intensity.

The strand 400 is guided by a sheave 402 (similar to sheave 304) to shift or play transversely of the grasping width of belts 404 and 406 which are looped at their upper extremities about sheaves 408 and 410 respectively, and at their lower portions under sheaves 412 and 414.

It will be noted that all of the sheaves are of the same diameter and that the upper sheaves are spaced radially and rotate on substantially coplanar horizontal axes 416 and 418. Similarly, the lower sheaves are spaced radially and are rotatable on axes 420 and 422 arranged in substantial horizontal alignment. The sheave 412 extends partially between sheaves 410 and 414 and 408 and 410. The arrangement of the sheaves deflects the advance flights 424 and 426 of the belts to form a modified S-shaped grasping zone which at its downstream end terminates at the discharge zone 428 of the mechanism.

The drawing assembly may be shielded by a member 430 which may have a slit 432 in alignment with the intake between the upper ends of the advance flights to guide the strand into the drawing mechanism when the process is first begun.

The drawing mechanism may be driven by a motor 434 connected to sheave 412.

In each of these designs the centrifugal force together with the initial tensioning adjustment grasps the strand, and the strand is drawn on a curved surface over an extensive length thereof. A gentle grasp is achieved together with the requisite frictional development to obtain the desired pull on the material without deforming the material or fracturing the same.

It will be understood that the guide wheel shown in the latter two embodiments may be substituted for the centering fork shown in the first several embodiments.

What is claimed is:

1. Apparatus for attenuating strands of material comprising a pair of belts having opposing strand-grasping sections transversely deflected to produce a flowing approximately S-shaped grasping zone terminating in a discharge end, said belts arranged to rotate about axes to develop centrifugal forces biasing the belts towards each other, and discharge accentuating means for casting of said strand loose from said belts at said discharge end of said grasping zone and comprising a sheave rotatably supporting at least one belt and provided with a non-round peripheral surface tracking said belt thereabout for oscillating the belt transversely and guiding the belt to move sharply away from the strand so as to cast loose therefrom.

2. In an apparatus for drawing glass strand, a pair of flat belt loops, a sheave disposed within each end of each loop and provided with a crowned peripheral surface in contact with the internal surface of the associated loop, said loops having corresponding lengths disposed in press-

ing contact with each other along complementary grasping surfaces defining an intake at one end and a discharge at the other end, and strand guide means comprising a sheave with a peripheral transaxially diagonal groove adapted to receive the strand at said intake and pursuant to rotation thereof to course the strand laterally on said belts as said strand is being drawn between said grasping surfaces, all of said sheaves mounted on parallel axes and said groove having a lateral traverse less than the width of said belts.

3. In an apparatus for drawing glass strand a pair of belt loops, rotatable support means disposed within each end of each loop in contact with the internal side of the associated loop, said loops having corresponding lengths disposed in pressing contact with each other along complementary grasping surfaces providing an intake at one end and a discharge at the opposite end, and vibrating means operatively associated with at least one of said loops for oscillating the same sharply transversely at said discharge for stripping the strand therefrom.

4. Apparatus according to claim 3 and said vibrating means comprising a nonround face on the rotatable support means associated with said one loop at said discharge, said rotatable support means movable at a substantial speed sufficient to obtain a rapid oscillatory effect on the belt loop.

5. Apparatus according to claim 4 and said nonround face comprising a series of flats and intervening crowned surfaces continuous between adjacent flats disposed about the periphery of said rotatable support means.

6. Apparatus according to claim 5 and driving means directly connected to said rotatable support means comprising said nonround face to accentuate oscillation thereby of the related belt loop.

7. A glass fiber drawing apparatus comprising two flat belt loops each passing about a wheel at each end, said loops engaging each other at a determined region and having an intake at one end and a discharge at the other, said wheels rotatable on generally horizontal axes, each wheel comprising a cylindrical periphery crowned at its axial extremes to retain the belt thereon, and only noncylindrical spots on the cylindrical periphery of the wheels at said discharge of said region.
